Primary Examiner—Louis S. Zarfas
Assistant Examiner—Deanne Levy(57) **CLAIM**

The ornamental design for a wire basket, as shown and described.

DESCRIPTION

FIG. 1 is a top, front perspective view of the wire basket, showing my new design;

FIG. 2 is a side elevation view;

FIG. 3 is a top plan view; and,

FIG. 4 is a bottom plan view.

The surface shading on the illustrated wire basket is intended only to show the character and contour of the surfaces and not surface indicia.
